(57) **CLAIM**

The ornamental design for a connector plug for electronic game machine, as shown and described.

DESCRIPTION

FIG. 1 is a front, top and right perspective view of a connector plug for electronic game machine showing a second embodiment our new design;

FIG. 2 is a rear, bottom and left perspective view thereof;

FIG. 3 is a front view thereof;

FIG. 4 is a rear view thereof;

FIG. 5 is a top plan view thereof;

FIG. 6 is a bottom plan view thereof; and,

FIG. 7 is a right side view thereof, a left side view being a mirror image thereof.

1 Claim, 2 Drawing Sheets
